UNITED STATES PATENT OFFICE.

JOHN W. EKSTEDT, OF BELLEVILLE, NEW JERSEY, ASSIGNOR TO WESTINGHOUSE LAMP COMPANY, A CORPORATION OF PENNSYLVANIA.

WIRE-COILING MACHINE.

Application filed February 23, 1927. Serial No. 170,125.

This invention relates, generally, to improvements in machines for coiling wire; and the invention has reference, more particularly, to a novel construction of machine 5 for automatically turning wire into spiral or helical formations, such as spiral springs, etc., and the novel construction of machine is more especially adapted to operate upon exceedingly fine hairlike wire to coil the 10 same into very small spiral or helical formations suitable for use as incandescent electric lamp filaments.

The invention involves the provision, in a machine of the kind mentioned, of a means 15 for directly forming wire into continuous spiral or helical coils without the aid of a mandrel; said means comprising a novel construction of forming die, and a novel relation of said forming die to a means for 20 forcibly and continuously feeding the wire into operative engagement therewith, to the end that a uniform diameter, as well as uniform spacing and pitch of the coils is attained through the length of the produced 25 formation, even when exceedingly fine sizes of wire producing exceedingly small diameters of coiled formations is employed.

Another object of this invention is to provide, in a machine of the kind mentioned, 30 an improved automatic mechanical cut-off for dividing the spiral or helical formation delivered from the forming die into desired predetermined lengths or sections ready for use.

Other objects of this invention, not at this time more particularly enumerated, will be clearly understood from the following detailed description of the same.

With the various objects of this invention 40 in view, the same consists, primarily, in the novel wire coiling machine hereinafter set forth; and the invention consists, furthermore, in the novel arrangements and combinations of the several devices and parts, as 45 well as in the details of the construction of the same, all of which will be more fully described in the following specification, and then finally embodied in the claims appended thereto.

The invention is clearly illustrated in the accompanying drawings, in which:—

Fig. 1 is a plan view of the novel wire coiling machine, made according to and embodying the principles of this invention;

Fig. 2 is a side elevation of the same;

Fig. 3 is a fragmentary longitudinal section, taken on line 3—3 in Fig. 1;

Fig. 3^A is a detail transverse section taken on line 3^A—3^A in Fig. 1;

Fig. 4 is a fragmentary longitudinal section, drawn on an enlarged scale, of the forming die in operative relation to the wire feeding or force wheels; and

Fig. 5 is a detail horizontal section, taken on line 5—5 in Fig. 4.

Similar characters of reference are employed in all of the hereinabove described views, to indicate corresponding parts.

Referring now to the drawings, the reference character 1 indicates a suitable base upon which the wire coiling mechanism is mounted. Fixed upon said base 1 by its bed-plate 2 is a pedestal 3. Journaled to extend transversely through the upper forward end of said pedestal 3 is a spindle 4, upon one end of which is suitably secured a driven wire feeding or force wheel 5, having a grooved periphery to embrace the under-side of a wire 6 which is led over the same.

Extending upwardly at each side of the rear end of said pedestal 3 are transversely opposed perforate ears or lugs 7, in which is supported a hinge pintle 8. Pivotaly connected upon said hinge pintle 8 is a swing- 80 ing frame 9, which extends forwardly above 85 said pedestal 3, and which may be swung toward or away from the latter. Journaled to extend transversely through the forward or free end of said frame 9 is a spindle 10, upon one end of which is suitably secured 90 an idler wire feeding or force wheel 11, also having a grooved periphery to embrace the upper side of the wire 6 which passes beneath the same, when said frame 9 is swung down to position said idler wire feeding or 95 force wheel 11 in operative relation to the driven wire feeding or force wheel 5 and the said wire 6 which passes over the latter. A means is provided for locking down the 100 frame 9 to hold the wire feeding or force wheel 11 in operative relation to the wire feeding or force wheel 5, whereby the wire 6 is pinched therebetween, and will consequently be operatively fed forward by the 105 rotation of the said drive wheel 5. This means comprises a latch-bar 12, which is pivotally connected by the pivot pin 13 to the lower portion of said pedestal 3, to extend upwardly through a slot 14 at the top of said pedestal 3, and having its free extrem-

110

ity 15 exteriorly and upwardly projected through a slot 16 in said swinging frame 9. Connected with said frame 9 is a fixed cross-pin 17. Said latch-bar 12 is provided with a notch 18, having an inclined upper side 19, which when the latch-bar is thrust toward the cross-pin 17, engages the latter so as to exert a downward thrust thereon, to thus press downwardly said frame to hold the 10 idler wire feeding or force wheel 11 operatively related to the wheel 5 and wire 6 engaged therebetween. Said latch-bar 12 is yieldably and releasably held in the above described operative relation to said cross-pin 15 17 by means of a spring actuated thrust-pin 20, which is mounted in a slideway 21 provided in the forward portion of said pedestal 3. The spring 22 which actuates said thrust-pin 20 is backed by a threaded plug 23 which screws into said pedestal 3, as 20 shown, more particularly in Figure 3.

A suitable power transmission means for rotating said driven wire feeding or force wheel 5 is provided, which in the preferred 25 form, comprises an electric motor 24, as the source of power, the same being conveniently mounted on a bracket or shelf 25 connected with said base 1. Mounted on said base 1 in alignment with the spindle 4 of said driven 30 wire feeding or force wheel 5, is a housing 26 having a bearing portion 27 in which is journaled a transverse shaft 28. Loosely mounted on said transverse shaft 28 is a worm gear 29. Also journaled in connection 35 with said housing 26 is one end of a drive shaft 30, which is operatively coupled at its outer end with the motor 24 so as to be driven thereby. Fixed on the inner end of said drive shaft 30 is a worm 31, which operatively 40 meshes with and drives the worm gear 29. Keyed to said transverse shaft 28 is a clutch-sleeve 32, having at its inner end male clutch jaws 33, adapted to be brought into clutched engagement with female clutch 45 jaws 34 provided in connection with the hub of said worm gear 29, so that the latter by the manipulation of the clutch mechanism may be engaged or disengaged at will with the transverse shaft 28. Said clutch-sleeve 50 32 possesses an annularly grooved exterior end 35, to receive the connection therewith of a clutch shift-lever 36, which is pivoted upon a fulcrum ear 37 provided in connection with said housing 26. Arranged intermediate said transverse shaft 28 and the spindle 4 of the driven wire feeding or force wheel 5, is a separable coupling member 38 having one end slidably secured to the transverse shaft 28 by a pin and slot connection 55 39, while its other end is socketed to engage over the end of the spindle 4, the latter having a transverse pin 40 which enters the longitudinal slots 41, when the parts are operatively joined together, so that rotary 60 movement of the transverse shaft 28 is trans-

mitted to the spindle 4. The arrangement provided by the coupling member 38 permits the spindle 4 to be disconnected from the transverse shaft 28 when desired, so that adjustments of the wire relative to the wheels 5 and 11 may be more easily accomplished.

The reference character 42 indicates a bearing or support for rotatably mounting, adjacent to the rear end of the base 1, a spool 43 upon which is wound a supply of the wire 6.

Mounted on the base 1, intermediate the spool 43 and the pedestal 3, is a standard or bracket 44 provided with an outwardly projecting journal stud 45. Rotatably mounted on said journal stud 45 is a measuring reel 46 of suitable diameter. The wire 6 from said supply spool 43 is led under and around the circumference of said measuring reel 46, thence passing to and between said wire feeding or force wheels 5 and 11. Formed in connection with the rear end of said pedestal 3 is a rearwardly projecting bracket extension 47 adjacent to the end of which is rotatably mounted an idler guide wheel 48, having a grooved periphery over which the wire 6 is guided as it passes to said wire feeding or force wheels 5 and 11. Suitably secured to said bracket extension 47 is a preferably resilient transversely projecting supporting arm 49, upon the free end of which is supported a lubricating pad 50, made of felt or any other suitably absorbent material adapted to be saturated with oil or other desired lubricant. The supporting arm 49 so supports the pad 50, that the latter is borne into engagement with the wire 6, as the latter moves from the guide wheel 48 to the wire feeding or force wheels 5 and 11, thus lubricating the surface of the wire, to thereby reduce friction between the same and the wire coiling die, into operative engagement with which said wire feeding or force wheels 5 and 11 propel said wire.

Connected with the forward end of said pedestal 3 is a longitudinally projecting bracket or shelf 51, upon which is supported an adjustable means for mounting a wire coiling die 52. The adjustable supporting means for the die comprises a carrier member 53 supported in connection with said bracket and shelf 51, for horizontal swinging adjustment, by means of a pivot stud 54. In order to provide means for making the side to side swinging adjustment of said carrier member 53, and at the same time retain the same in desired adjusted position, the said carrier member 53 is provided with a tail-piece 55 of reduced width, which extends between a pair of upstanding stationary lugs 56 provided in connection with said bracket or shelf 51. Each lug 56 is provided with an adjusting screw 57, which respectively bear against opposite sides of said tail-piece 55. By relaxing one screw

and turning home the other screw, the carrier member 53 may be swung in one direction to the desired degree, and thereupon held in such adjusted position, or by turning 5 home the first mentioned screw and relaxing the second mentioned screw, adjustment to the desired degree may be made in the opposite direction. Pivotally connected with said carrier member 53, for vertical swing- 10 ing or up and down adjustment, is a saddle or die-holder 58 provided with a longitudinal opening 59 through which the die 52 extends. The adjustment of said saddle or die-holder 58 is controlled by an adjusting 15 screw 60, which passes through the free end of said saddle or die-holder. Adjustably secured by the set-screw 61 to the tail end of the die 52 is a depending arm 62, provided in its lower end with a stud or dowel 20 63 which enters a socket 64 provided in the outer end of the carrier member 53. Threaded through said arm 62, intermediate the die 52 and the stud or dowel 63 is an adjustable stop-screw 65, which is 25 stopped against the outer end of said carrier member 53 when the die is in operative supported relation to the saddle or die-holder 58. The adjustment of the carrier-member 53 and saddle or die-holder 58 will determine 30 the position of the operative end of the die 52, so that the same will be opposed to and properly aligned with the meeting peripheries of the wire feeding or force wheels 5 and 11, so as to properly receive 35 the wire 6 fed forward by the latter. The longitudinal adjustment of the die 52 is determined by manipulating the stop-screw 65. When once such adjustment is made, the die 52 may be locked against rearward movement by the set screw 66 which is threaded 40 downwardly through the saddle or die holder 58. If for any reason it is desired to remove the die 52, without disturbing the adjustments, so that the same can be re- 45 turned to the same predetermined operative position, the set-screw 66 may be relaxed, and the die 52 thereupon may be withdrawn from the saddle or holder 58. When returned to the saddle or holder its desired 50 predetermined position will be regained, for the reason that the adjusted stop-screw 65 will, by re-engagement with the outer end of the carrier member 53, limit the inward movement to the predetermined degree. 55 The operative end of the die 52 is formed to provide a substantially semicircular die-depression 67 of a width corresponding to the diameter of wire to be worked upon, and of a radius corresponding to the radius of 60 the helix to be formed. The outer side face of the die is provided with a tapered shear portion 68 which determines the spacing between the coils of the spiral or helical formation produced by the die. 65 In operation the wire 6 is led forward from the measuring reel 46, over the guide wheel 48, and thence between the grooved peripheries of the wire feeding or force wheels 5 and 11. The spindle 4 of the wire feeding or force wheel 5 being coupled with 70 the transmission mechanism, the clutch of the latter is thrown in, whereby power is transmitted to the wire feeding or force wheel 5, the rotation of which pinches the wire 6 between its periphery and the periphery of the wire feeding or force wheel 11, thus causing the wire 6 to be forced end- 75 wise into engagement with the die 52, and at the same time drawing the wire from the supply spool 43, and rotating, during 80 the operation, the measuring reel 46. The end of the wire 6, thus forced toward the die 52 enters the die-depression 67 and it is curled upwardly and over by engagement therewith, as shown in Fig. 4; the formed 85 coils are at the same time caused to rotate so that as the wire passes out of the die-depression 67 it is carried around against the outer face of the shear portion 68, which thus enters between the turns of the coils 90 whereby the same are uniformly spaced apart. In practice the operative end of the die 52 is positioned intermediate the peripheries of the wire feeding or force wheels 5 and 11, as near to the pinching point of the latter as possible. In order to prevent displacement of the wire from the grooved periphery of the wheel 5, as the wire moves beyond the pinching or gripping points of 95 the wheels 5 and 11, a resilient keeper finger 100 69 is provided, the body of which is supported on and attached to the underside of the free end of the frame 9, so that its free end bears downwardly upon the wire, and thus holds the same against displacement 105 from the periphery of the wheel 5 while moving toward the die, and consequently assures a proper lead of the wire into the die-depression 67 of said die. Since the keeper finger 69 is supported by the swing- 110 ing frame 9, it will be removed from operative position when the frame 9 is swung upward, and consequently will not impede the operations of initially disposing and relating the wire to the force wheel 5. As 115 the operation continues, the spiral or helical formation 6' produced will continuously move transversely outward, as shown in Fig. 1. A novel means, actuated by the rotation of the measuring reel 46, is provided 120 for severing the spiral or helical formation 6' into suitable predetermined length. This means consists in an automatic cut-off mechanism, which comprises a suitable standard or support 70 mounted on the base 1, 125 preferably in such manner, that the same may be swung outwardly from a normal operative position in alignment with the spiral or helical formation 6', this arrangement being effected by pivotally connecting 130

one end of the standard 70 to the base 1, and providing a lock-screw device 71 to engage the slotted end 72 of the standard 70, and thus lock the same in normal operative position. Supported by said standard is a tubular guide element 73 through which the formation 6' moves as it issues outwardly from the die 52. Pivoted upon a fulcrum stud 74, which projects from the outer face of said standard 70, is a bell-crank lever 75, provided at its upper end with a cutting-blade 76, which by the oscillation of said bell-crank lever 75 is carried transversely across the exit end of said guide element 73, whereby that portion of the formation 6', which has issued from the guide element, is severed from the main body thereof. The guide element 73 is longitudinally adjustable in the standard 70, so that its exit end may be operatively adjusted relative to the cutting-blade 76, the guide element being retained in proper adjusted position by means of a set-screw 77 which is threaded into the upper end of said standard 70. The means for actuating the bell-crank lever 75, comprises a vertically reciprocable member 78 which is slidable through the base 1 and the bottom flange of said standard 70. Said member 78 is provided at its upper end with an annularly grooved head 79, in which is engaged the end stud 75' of the lower arm of said bell-crank lever 75. Said standard 70 is provided with a socketed portion 80, in which is arranged a push-pin 81 subject to the thrust of a compression spring 82 which is arranged in said socketed portion 80 and held in place by a plug 83. Said push-pin 81 thrust against the upper arm of said bell-crank lever 75 to hold the same with the cutting-blade 76 in normal initial position (see Figure 2). The means for producing the properly timed operative movement of said bell-crank lever 75 and its cutting-blade 76 is controlled by the measuring reel 46, in such manner, that upon completion of each rotation of the latter the former devices are operated. It follows, therefore, that the size of the measuring reel 46 will determine the length of the severed portions of the formation 6', since the circumference of said measuring reel determined the amount of wire fed forward and formed into the spiral or helical formation intermediate each operation of the cutting-blade 76. The larger the measuring reel the longer will be the severed portion of the formation, and conversely, the smaller the measuring reel the shorter will be the severed portion of the formation. Said means for actuating the bell-crank 75 and cutting blade 76, comprises a cam 84 arranged to rotate with said measuring reel 46, and possessing a step 85 intermediate its high and low point. Pivoted to said standard 45 or bracket 44 is a trip-lever member 86 having at its upper end an off-set nosing 87 which is engageable with the perimeter of the cam 84. The lower end of said lever member 86 extends downwardly through the base 1, and a pull spring 88 is provided to yieldably hold the nosing 87 of said lever member in riding engagement with the perimeter of said cam 84. Pivotedly connected with the lower end of said lever member 86 is a trip-pawl 89, yieldably held in normal upward projection by a pull-spring 90. Pivotedly mounted on a fulcrum block 91 so as to extend beneath the base 1 is a rocking lever 92, the forward end of which is operatively engaged with the lower end of said vertically reciprocable member 78, while its rearward end is provided with a downwardly off-set nosing 93. As the measuring reel 46 begins its rotation, the nosing 87 of the lever member 86 is swung outwardly by the rise of the cam 84, thereby swinging the lower end of said lever member 86 toward the adjacent end of the rocking lever 92, whereby the trip-pawl 89 is carried forward past the nosing 93 the pawl yielding to engagement with the latter. As the measuring reel 46 completes its rotation, the step 85 of the cam 84 is brought opposite the nosing 87 of the lever member 86, which thereby permits a quick drop of the nosing 87 from the high point of the cam 84 back to the low point thereof, the lever member 86 thereby swinging in the opposite direction under the pull of the spring 88. This quick return oscillation of the lever member 86 thus effected, causes the rearward swinging movement of the lower end thereof, whereby the trip-pawl 89 is moved against the nosing 93 of the rocking lever 92, and since the trip-pawl is unyieldable when moved in such direction, its passing engagement with the nosing 93 produces a lifting effect upon the latter, which swings upward its rearward end and downward its forward end. The downward swing of the forward end of said rocking lever 92, pulls downwardly the vertically reciprocable member 78, thereby in turn rocking the bell-crank lever 75 on its fulcrum to carry said cutting blade 76 into severing engagement with that portion of the formation 6' which has issued from the guide element 73. The above described operations are repeated at each revolution of the measuring reel. 55

I am aware that some changes may be made in the various arrangements and combinations of the several devices and parts, without departing from the scope of my present invention as above described, and as defined in the appended claims. Hence I do not limit my invention to the exact arrangements and combinations of parts as described in the foregoing specification, nor 60

do I confine myself to the exact mechanical details of the construction of said parts as illustrated in the accompanying drawings.

What is claimed is:

5. 1. In a machine of the kind described, the combination with a pair of wire feeding wheels having grooved peripheries, of a wire coiling die having a substantially semicircular die-depression substantially corresponding in width to the diameter of the wire to be worked upon, said die being so disposed that said die-depression receives the wire directly from the grooved peripheries of said feeding wheels adjacent to the pinching point of the latter. 70
2. In a machine of the kind described, the combination with a pair of wire feeding wheels having grooved peripheries, of a wire coiling die having a substantially semicircular die-depression substantially corresponding in width to the diameter of the wire to be worked upon, said die being so disposed that said die-depression receives the wire directly from the grooved peripheries of said feeding wheels adjacent to the pinching point of the latter, and said die having a chamfered side face to form a shear member at one side of said die-depression for spacing the convolutions into which the wire is formed by engagement with the die. 80
3. In a machine of the kind described, the combination with a pair of wire feeding wheels having grooved peripheries, of a wire coiling die having a substantially semicircular die-depression substantially corresponding in width to the diameter of the wire to be worked upon, said die being entered between the wire discharging sides of said feeding wheels with its die-depression opposed to and adjacent to the pinching point of said feeding wheels. 90
4. In a machine of the kind described, a driven wire feeding wheel, stationary means for mounting the same, an idler wire feeding wheel, a movable frame in which said latter wheel is mounted, whereby the same may be tangentially opposed in operative relation to said driven wire feeding wheel, means for tensionally holding said frame and idler wire feeding wheel in operative position, a power transmission means for actuating said driven wire feeding wheel, and a wire coiling die having a substantially semicircular die-depression opposed to and adjacent to the pinching point of said feeding wheels. 100
5. In a machine of the kind described, the combination with a pair of wire feeding wheels having grooved peripheries, of a wire coiling die having a substantially semicircular die-depression substantially corresponding in width to the diameter of the wire to be worked upon, said die being entered between the wire discharging sides of said feeding wheels, with its die-depression opposed to and adjacent to the pinching point of said feeding wheels. 110
6. In a machine of the kind described, the combination with a pair of wire feeding wheels having grooved peripheries, of a wire coiling die having a substantially semicircular die-depression substantially corresponding in width to the diameter of the wire to be worked upon, said die being entered between the wire discharging sides of said feeding wheels, with its die-depression opposed to and adjacent to the pinching point of said feeding wheels, and means for adjustably supporting said die in operative relation to said feeding wheels. 120
7. In a machine of the kind described, a driven wire feeding wheel, stationary means for mounting the same, an idler wire feeding wheel, a movable frame in which said latter wheel is mounted whereby the same may be tangentially opposed in operative relation to said driven wire feeding wheel, means for tensionally holding said frame and idler wire feeding wheel in operative position, a power transmission means for actuating said driven wire feeding wheel, and a wire coiling die having a substantially semicircular die-depression opposed to and adjacent to the pinching point of said feeding wheels. 130
8. In a machine of the kind described, a driven wire feeding wheel, stationary means for mounting the same, an idler wire feeding wheel, a movable frame in which said latter wheel is mounted whereby the same may be tangentially opposed in operative relation to said driven wire feeding wheel, means for tensionally holding said frame and idler wire feeding wheel in operative position, a power transmission means for actuating said driven wire feeding wheel, and a wire coiling die having a substantially semicircular die-depression opposed to and adjacent to the pinching point of said feeding wheels, and means for adjustably supporting said die in operative relation to said feeding wheels. 140
9. In a machine of the kind described, the combination with a pair of wire feeding wheels having grooved peripheries, of a wire coiling die having a substantially semicircular die-depression substantially corresponding in width to the diameter of the wire to be worked upon, said die being entered between the wire discharging sides of said feeding wheels, with its die-depression opposed to and adjacent to the pinching point of said feeding wheels, a wire guide-wheel aligned with and spaced rearwardly from said feeding wheels, a wire lubricating means intermediate said feeding wheels and said guide wheel, and means for supporting said lubricating means in contact with the 150

wire passing between said guide wheel and feeding wheels.

10. In a machine of the kind described, a driven wire feeding wheel, stationary means for mounting the same, an idler wire feeding wheel, a movable frame pivotally connected with said stationary means in which said latter wheel is mounted whereby the same may be tangentially opposed in operative relation to said driven wire feeding wheel, means for tensionally holding said frame and idler wire feeding wheel in operative position, an idler wire guide wheel aligned with and spaced rearwardly from said feeding wheels, a wire lubricating means intermediate said feeding wheels and said guide wheel, means for supporting said lubricating means in contact with the wire passing between said guide wheel and feeding wheels, a power transmission means for actuating said driven wire feeding wheel, and a wire bending die having a substantially semicircular die-depression opposed to and adjacent to the pinching point of said feeding wheels.

11. In a machine of the kind described, a driven wire feeding wheel, a stationary means for mounting the same, an idler wire feeding wheel, a movable frame pivotally connected with said stationary means in which said latter wheel is mounted whereby the same may be tangentially opposed in operative relation to said driven wire feeding wheel, means for tensionally holding said frame and idler wire feeding wheel in operative position, an idler wire guide wheel aligned with and spaced rearwardly from said feeding wheels, a wire lubricating means intermediate said feeding wheels and said guide wheel, means for supporting said lubricating means in contact with the wire passing between said guide wheel and feeding wheels, a power transmission means for actuating said driven wire feeding wheel, a wire coiling die having a substantially semicircular die-depression opposed to and adjacent to the pinching point of said feeding wheels, and means for adjustably supporting said die in operative relation to said feeding wheels.

12. In a machine of the kind described, the combination with a pair of grooved tangential wire feeding wheels, of a wire coiling die having a substantially semicircular die-depression opposed to and adjacent to the pinching point of said feeding wheels, means for supplying wire to said feeding wheels, a rotatable measuring reel intermediate said feeding wheels and said wire supplying means around which the wire is passed, a tubular guide to receive the coiled wire formation issuing from said die, a cutting-blade reciprocable across the discharge end of said tubular guide, a lever mechanism for actuating said cutting-blade,

and a cam-means rotated by said measuring reel for operating said lever mechanism.

13. In a machine of the kind described, the combination with a pair of grooved tangential wire feeding wheels, of a wire coiling die having a substantially semicircular die-depression opposed to and adjacent to the pinching point of said feeding wheels, means for supplying wire to said feeding wheels, a rotatable measuring reel intermediate said feeding wheels and said wire supplying means around which the wire is passed, means to support the coiled wire formation issuing from said die, and means actuated by the rotation of said measuring reel for severing the coiled wire formation passed through said support into predetermined lengths.

14. In a machine of the kind described, the combination with a wire coiling means and means for feeding wire into operative engagement therewith, of a rotatable measuring reel around which the wire passes to said feeding means, means to support the coiled wire formation issuing from said coiling means, and means actuated by the rotation of said measuring reel for severing the coiled wire formation passed through said support into predetermined lengths.

15. In a machine of the kind described, the combination with a wire coiling means and means for feeding wire into operative engagement therewith, of a rotatable measuring reel around which the wire passes to said feeding means, means to support the coiled wire formation issuing from said coiling means, and means actuated by the rotation of said measuring reel for severing the coiled wire formation passed through said support into predetermined lengths, comprising a pivoted bell-crank lever having at one end a cutting-blade movable across the exit end of said support, a reciprocable means engaged with the opposite end of said bell-crank lever, a rocking lever for actuating said reciprocable means, and means actuated by the rotation of said measuring reel for operating said rocking-lever.

16. In a machine of the kind described, the combination with a wire coiling means and means for feeding wire into operative engagement therewith, of a rotatable measuring reel around which the wire passes to said feeding means, means to support the coiled wire formation issuing from said coiling means, and means actuated by the rotation of said measuring reel for severing the coiled wire formation passed through said support into predetermined lengths, comprising a pivoted bell-crank lever having at one end a cutting-blade movable across the exit end of said support, a reciprocable means engaged with the opposite end of said bell-crank lever, a rocking-lever for actuating said reciprocable means, a pivoted trip-

lever having at one end a trip-pawl yieldable in one direction, said rocking-lever having a nosing engageable by said trip-pawl, and a cam means rotated by said measuring 5 reel for actuating said trip-lever.

17. In a machine of the kind described, the combination with a wire coiling means and means for feeding wire into operative engagement therewith, of a rotatable measuring reel around which the wire passes to 10 said feeding means, means to support the coiled wire formation issuing from said coiling means, and means actuated by the rotation of said measuring reel for severing 15 the coiled wire formation passed through said support into predetermined lengths, comprising a pivoted bell-crank lever having at one end a cutting-blade movable across the exit end of said support, spring 20 means for disposing said bell-crank lever and its cutting-blade in normal initial position, means for actuating said bell-crank lever, and a cam means rotated by said measuring reel for operating said bell-crank 25 actuating means.

18. In a machine of the kind described, the combination with a wire coiling means and means for feeding wire into operative engagement therewith, of a rotatable measuring reel around which the wire passes to 30 said feeding means, a tubular guide to receive the coiled wire formation issuing from said wire coiling means, a pivoted bell-crank lever having at one end a cutting-blade movable across the exit end of said tubular guide, a vertically reciprocable member engaged 35 with the opposite end of said bell-crank member, a pivoted rocking-lever having one end engaged with said vertically reciprocable member and having an off-set nosing at 40 its opposite end, spring means for disposing said bell-crank lever and associated parts in normal initial position, a pivoted trip-lever, a cam means operated by the rotation of said measuring reel for actuating 45 said trip-lever, spring means for holding one end of said trip-lever in operative relation to said cam means, and a trip-pawl on the free end of said trip-lever, said trip-pawl 50 being operatively non-yieldable to said off-set nosing of said rock-shaft upon movement of said trip-lever in operative direction but yieldable thereto during the reverse movement of said trip-lever.

55 19. In a machine of the kind described, the combination with a pair of tangential

wire feeding wheels having grooved peripheries, of a wire coiling die having a substantially semi-circular die-depression substantially corresponding in width to the diameter of the wire to be worked upon, said die being entered between the wire discharging sides of said feeding wheels, with its die-depression opposed to and adjacent to the pinching point of said feeding wheels, a tubular guide to receive the coiled wire formation issuing from said die, a pivoted bell-crank lever having at one end a cutting-blade movable across the exit end of said tubular guide, and means for intermittently actuating said bell-crank lever and its cutting blade. 60

20. In a machine of the kind described, the combination with a pair of tangential grooved wire feeding wheels, of a wire coiling die having a substantially semicircular die-depression substantially corresponding in width to the diameter of the wire to be worked upon, said die being entered intermediate the discharge side of the peripheries 75 of said feeding wheels, with its die-depression opposed to and adjacent to the pinching point of said feeding wheels, a rotatable measuring reel around which the wire passes to said feeding wheels, a tubular guide to receive the coiled wire formation issuing from said die, a pivoted bell-crank lever having at one end a cutting-blade movable across the exit end of said tubular guide, a vertically reciprocable member engaged 80 with the opposite end of said bell-crank member, a pivoted rocking-lever having one end engaged with said vertically reciprocable member and having an off-set nosing at its opposite end, spring means for disposing 85 said bell-crank lever and associated parts in normal initial position, a pivoted trip-lever, a cam means operated by the rotation of said measuring reel for actuating said trip-lever, spring means for holding one end of said trip-lever in operative relation to said cam means, and a trip-pawl on the free end of said trip-lever, said trip-pawl 90 being operatively non-yieldable to said off-set nosing of said rock-shaft upon movement of said trip-lever in operative direction but yieldable thereto during the reverse movement of said trip-lever. 95

In testimony whereof, I have hereunto subscribed my name this eleventh day of February, 1927.

JOHN W. EKSTEDT.
